UNITED STATES PATENT OFFICE.

LAWRENCE A. WAGNER, OF YOUNGSTOWN, OHIO.

PLASTIC FENCE-POST.

1,162,322.

Specification of Letters Patent.

Patented Nov. 30, 1915.

Application filed September 10, 1914. Serial No. 861,019.

To all whom it may concern:

Be it known that I, LAWRENCE A. WAGNER, a citizen of the United States, residing at Youngstown, in the county of Mahoning and State of Ohio, have invented certain new and useful Improvements in Plastic Fence-Posts, of which the following is a specification.

My invention relates to improvements in fence-posts, and has particular reference to plastic fence-posts, provided with metallic reinforcing, and having means to secure strands of wire thereto in a manner to prevent longitudinal slipping of the wire.

An important object of the invention is to provide a post of the above mentioned character, which is simple in construction, inexpensive to manufacture, strong, durable, and convenient in use.

Other objects and advantages of the invention will be apparent during the course of the following description.

In the accompanying drawings forming a part of this specification and in which like numerals are employed to designate like parts throughout the same, Figure 1 is a perspective view of a fence-post embodying my invention, Fig. 2 is a longitudinal sectional view through the same, taken on line 2—2 of Fig. 1, and Fig. 3 is a horizontal sectional view taken on line 3—3 of Fig. 2.

In the drawings, wherein for the purpose of illustration is shown a preferred embodiment of my invention, the numeral 5 designates a fence-post, formed of plastic material, such as concrete or the like. This post is preferably square in cross-section, longitudinally tapered and increases in width downwardly, as shown.

The numeral 6 designates U-shaped metallic reinforcing members, forming longitudinal rods 6', disposed near the corners of the post, as shown.

The post 5 is provided upon one side or face with a longitudinal groove 9, which is V-shaped in horizontal cross-section, as more clearly shown in Fig. 3. The post 5 is provided with spaced transverse horizontal openings 10, which lead into the groove 9, as more clearly illustrated in Fig. 2. Disposed within the transverse openings 10 are preferably metallic telescoping tubes 11 and 12, provided respectively at their outer ends with flanges 13 and 14, the flanges 14 being

V-shaped in horizontal cross-section, to properly fit within the groove 9, the same extending over and about the edges of the groove to protect the same, as more clearly shown in Fig. 3.

Extending within the inner tubes 11 are longitudinally adjustable tying-elements or bolts 15, having corresponding ends preferably provided with hooks 16 to receive the strands of wire 16', while their opposite ends are preferably screw-threaded for receiving adjusting nuts 17, which engage the flanges 13, as shown.

The strands of wire 16' are passed through the hooks 16, subsequently to which the adjusting nuts 17 are manipulated to draw the tying-elements 15 inwardly, portions of the strands of wire being drawn within the V-shaped flanges 14, whereby they are crimped and longitudinal creeping of the wire is effectually prevented.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A fence-post formed of plastic material and provided upon one face with a longitudinally extending groove formed V-shaped in cross-section and having transverse openings which lead into the groove, metallic sleeves arranged within the transverse openings and having substantially V-shaped flanges disposed within the groove, longitudinally adjustable tying-elements arranged within the transverse openings and having hooked heads disposed within the groove, and means to longitudinally adjust the tying-elements.

2. A fence-post formed of plastic material and provided upon one face with a longitudinally extending groove and having transverse openings leading into the groove, metallic sleeves arranged within the transverse openings and having flanged ends fitting within the longitudinal groove, a corresponding number of metallic sleeves telescoping with the first named metallic sleeves and arranged within the transverse open-

ings and having their outer ends flanged and engaging with the side of the post, longitudinally adjustable bolts extending through the sleeves and having eyes upon corresponding ends for receiving strands of wire to draw them into the longitudinal groove, and nuts having screw-threaded engagement with the opposite ends of the bolts to move them

longitudinally and engaging with the flanges of the second named sleeves.

In testimony whereof I affix my signature in presence of two witnesses.

LAWRENCE A. WAGNER.

Witnesses:

B. P. FISHBURNE,
WYNNE JOHNSON.
